UNITED STATES PATENT OFFICE.

HARRY M. PFLAGER, OF ST. LOUIS, MISSOURI.

CAR-UNDERFRAME.

No. 863,871.

Specification of Letters Patent. Patented Aug. 20, 1907.

Application filed March 9, 1907. Serial No. 361,522.

To all whom it may concern:

Be it known that I, HARRY M. PFLAGER, a citizen of the United States, residing at St. Louis, in the State of Missouri, have invented a new and useful Improvement in Car-Underframes, of which the following is a specification.

My invention relates to the underframe of a railroad car, and has for its object to produce a metallic underframe in which the body-bolsters are connected rigidly to each other by middle longitudinal beams, and to the side and end sills respectively, by diagonal members or braces, all in the same horizontal plane, for enabling the stress of the draft-gear applied directly to the body-bolsters at their middle portion, to be transmitted thereby to the best advantage through the said beams and sills, and for transmitting any stress or shock coming immediately on the center part or ends of the end sills, to the body-bolsters at their junction with the said beams, or maximum resisting part of the underframe.

The invention consists in features of novelty as hereinafter described and claimed, reference being had to the accompanying drawing forming part of this specification, whereon,

Figure 1, is a top plan view of my improved metallic car underframe; Fig. 2, a vertical longitudinal section to enlarged scale through one of the body-bolsters and adjacent end part of the underframe on line 2, 2, in Fig. 1; Fig. 3, a cross section through one of the transverse separators and needle-beams respectively, of the underframe on line 3, 3, in Fig. 1; Fig. 4, a vertical transverse section to enlarged scale through the underframe on line 4, 4, in Fig. 1, looking to the left, and showing the body-bolster in side elevation, and Figs. 5, and 6, similar views to Fig. 4, on lines 5, 5, and 6, 6, in Fig. 1, looking to the right, and showing the separators, and one of the needle-beams respectively, between the longitudinal members of the underframe, in side elevation.

Like letters and numerals of reference denote like parts in all the figures.

My improved metallic car underframe consists principally of the two body-bolsters *a* which are composed preferably of cast steel respectively integral, and connected to each other at the middle part of the underframe by two longitudinal, preferably channel-shaped beams *b* which are spaced a suitable distance apart, one on each side of the longitudinal center of the underframe, for enabling the application between them to each body-bolster *a*, of a suitable self-centering draft-gear *c* having a spring or springs without follower-plates on each side of the said center, such as that described in the Letters Patent of the United States granted to Harry M. Pflager, January 23, 1906, Number 810,805, for improvement in draft-gear for railroad cars, the end portions of the beams *b*, which are arranged with their webs vertical and their flanges outward toward

the side longitudinal sills *d* of the outer rectangular portion of the underframe, being in the present case inserted within openings *l*, formed transversely through the body-bolsters *a*, the webs of the beams *b* bearing 60 against the inner side walls *2*, of the openings *l*, to which they are rigidly fixed by rivets *3*. Along the top and bottom of the web of each beam *b* on its unflanged side between the body-bolsters *a* is riveted a reinforcing angle iron *4*, which butts (or not) endwise 65 against the inner sides of the body-bolsters *a*.

By making the beams *b* channel-shaped, with the angles *4* riveted thereto as described, I obtain, in those cases where the height of the beam is limited, a stronger section with less material than when made channel or 70 I-shaped with top and bottom cover plates riveted to the corresponding flanges thereof, in which case some of the metal of the greatest value is cut out for the rivet holes.

Overlapping and lying between the flanges of the 75 end portions of the beams *b* within the openings *l*, of each body-bolster *a*, are fixed by the rivets *3*, the inner end portions of two corresponding channel-shaped members *e*, having their webs vertical and flanges outward, similarly to the beams *b*, the members *e* 80 converging from the body-bolsters *a* to their outer ends which are fixed to the adjacent end sill *f* of the outer rectangular portion of the underframe by angles *5*, and rivets *6*, as shown, or in any other suitable manner.

The body-bolsters *a* are fixed at their ends by rivets 85 7, (or otherwise) directly to the side longitudinal sills *d*, and are further connected to the longitudinal sills *d* by diagonally arranged and preferably L-shaped bars or braces *g*, the inner ends of which overlap the corresponding end portions of the end sill convergent 90 members *e* and are secured thereto and to the beams *b* and body-bolsters *a* by the rivets *3*, the outer ends of the braces *g* being fixed to the side sills *d* and end sills *f* (preferably at the junction of the said sills with each other, or corners of the rectangular portion of the 95 underframe), by angles *7*, and rivets *8*, as shown, or otherwise as found most suitable.

The beams *b* are held apart from each other and from the side longitudinal sills *d* respectively, at suitable intervals between the body-bolsters *a*, by transverse 100 channel or other suitably shaped separators *9*, and *10*, which are fixed at their ends to the beams *b* and sills *d* by angles *11*, and rivets *12*. Furthermore, the beams *b* and side sills *d* are braced to each other transversely 105 by the needle-beams *h* which straddle and are riveted (or otherwise fixed) thereto to the beams *b*, and at their ends to the side sills *d* as shown, the bottom opening of each needle-beam *h* being spanned by preferably two angle bars *13*, which are riveted to the bottom reinforcing angle irons *4* of the beams *b* and at their ends 110 to the adjacent bottom members *14* of the needle-beams *h*. It will be noted in this connection that the

angle bars 13 being arranged side by side, as seen particularly in Fig. 3, and coöperating with the top and bottom members 14, and 15, of the needle-beams *h* the latter are adapted to be loaded at the ends and supported in the middle, or vice versa, according to whether the side or center sills are loaded excessively; that is to say, when loaded at the ends the members 13, 14, will be in compression, and conversely.

By the application of draft-gear without follower-plates such as that described in the said patent, directly to the body-bolsters *a*, the middle longitudinal beams *b*, which in the ordinary car construction are comparatively close together, due to the use and limitation in length of the follower-plates for the ordinary draft-gear, can be spaced wider apart and the load thereon and on the side longitudinal sills more equally distributed. Moreover, any stress on the end sills *f* and endwise on the side longitudinal sills *d* is concentrated and transmitted to the body-bolsters *a* at their junction with the middle longitudinal beams *b*, or along the line of maximum resistance of the under-frame.

What I claim as my invention and desire to secure by Letters Patent is,

25 1. A metallic underframe for a railroad car, comprising two side sills, two end sills, two body-bolsters fixed at their ends to the side sills, and having suitable draft-gear applied to the central portion thereof respectively, two middle longitudinal beams connecting the body-bolsters to each other, one on each side of the longitudinal

center of the car, and spaced apart an equal distance, or thereabout, from each other, and from the side sills, and two members fixed at one end to each of the said body-bolsters at the junction therewith of the said beams, the said members converging from the body-bolster and fixed at their other end to the corresponding end sill at its middle portion, all the said parts being arranged in the same horizontal plane, substantially as described and for the purpose set forth.

2. A metallic underframe for a railroad car, comprising two side sills two end sills, two body-bolsters fixed at their ends to the side sills, and having a suitable draft-gear applied to the central portion thereof respectively, two middle longitudinal beams connecting the body-bolsters to each other, one on each side of the longitudinal center of the car, and spaced apart an equal distance, or thereabout, from each other and from the side sills, two members fixed at one end to each body-bolster at the junction therewith of the said beams, and converging therefrom and fixed at their other end to the corresponding end sill at its middle portion, and two diagonally arranged braces fixed at one end to each body-bolster at the junction therewith of the said beams, and at their other end to the said sills, at the junction, or thereabout, of the said sills with each other, all the said parts being arranged in the same horizontal plane, or thereabout, substantially as described and for the purpose set forth.

In testimony whereof I have signed my name to this specification in the presence of two subscribing witnesses.

HARRY M. PFLAGER.
